(57) **CLAIM**

We claim the ornamental design for a tapered articulating arm assembly for wall-mounted display mount, as shown.

DESCRIPTION

FIG. 1 is a front isometric view of a tapered articulating arm assembly for a wall-mounted display mount, according to the new design;

FIG. 2 is a front elevation view of the tapered articulating arm assembly for wall-mounted display mount depicted in FIG. 1;

FIG. 3 is a right elevation view of the tapered articulating arm assembly for wall-mounted display mount depicted in FIG. 1;

FIG. 4 is a left elevation view of the tapered articulating arm assembly for wall-mounted display mount depicted in FIG. 1;

FIG. 5 is a top plan view of the tapered articulating arm assembly for wall-mounted display mount depicted in FIG. 1; and,

FIG. 6 is a bottom plan view of the tapered articulating arm assembly for wall-mounted display mount depicted in FIG. 1.

The broken lines in the drawings depict portions of the tapered articulating arm assembly for wall-mounted display mount that form no part of the claimed design.
